FREDERICK G. KEYES, OF CAMBRIDGE, MASSACHUSETTS, ASSIGNOR, BY MESNE ASSIGNMENTS, TO FRIGIDAIRE CORPORATION, A CORPORATION OF DELAWARE

ELECTRICAL CONTROL SYSTEM FOR REFRIGERATION

Application filed November 10, 1923. Serial No. 673,931.

My present invention relates to electrical control systems and to switches of the flowing mercury type useful therein and particularly to a time switch of this type. It further relates to a multiple pole switch of this type. Herein my switches are shown and described in connection with a new and novel electrical control system as applied to a refrigeration system, but the switching system is applicable in the arts generally.

Switches of the mercury flow type, which are desired in the present instance, generally comprise a sealed glass envelope having a quantity of mercury therein and electrode terminals sealed therethrough and the general mode of operation is to tip or tilt the envelope to cause the mercury therein to flow to or from the electrodes to affect the closing or opening of electric currents therethrough. Such switches have for certain conditions a filling of gas such as hydrogen or nitrogen.

The object of my invention is to provide an electrical control system and apparatus.

Another object of my invention is to provide a mercury switch for alternating the energization of two sets of electrical translating devices.

Another object of my invention is to provide a mercury switch in which the mercury takes a definite time to flow after the switch is tipped before sufficient mercury gathers to connect the electrode terminals through which it is desired to have current pass or to disconnect such electrodes.

In the accompanying drawings which form part of this application I have shown an embodiment of my invention which comprises two chambers having electrodes therein, said chambers being connected at the bottom by a capillary or flow restricting tube having therein another electrode, and said chambers being connected near their top by a tube for equalizing the pressure of the gases or mercury vapor in the two chambers. When the switch is tipped in the direction of one of the chambers and the mercury has flowed thereto an electrical connection will be established between the electrode or electrodes of said chamber and the electrode of the flow restricting tube. The electrical connection through the

electrode of the other chamber of the switch will remain established until the mercury flows away from the electrode thereof and the time of this flow is predetermined. I have also shown in the drawings an application of this switch of my invention to a refrigeration system and have described herein its function and operation as a part of such system.

In the drawings Fig. 1 is an elevation view of an embodiment of my switch which is tipped to secure the flow of mercury to one chamber and the establishment of an electrically conducting path therethrough.

Fig. 2 is an elevation view similar to Fig. 1 but showing the switch tipped for the establishing of a circuit through the other side thereof and showing the mercury therein as having flowed to said other side.

Fig. 3 is a vertical elevation of a switch embodying my invention in which there is sufficient mercury to connect the three electrodes thereof when the switch is in the vertical position.

Fig. 4 is a view similar to Fig. 3 showing a switch which is completely open when left to stand in the vertical position.

Fig. 5 is an elevation view showing the switch of my invention in a tipped position but in which the mercury has not yet flowed sufficiently to disrupt the connection through the higher side and establish the connection in the lower side.

Fig. 6 is a diagrammatic representation of a refrigeration system showing my switch in the electrical control system thereof.

Fig. 7 is an end view of the switch tilting mechanism.

Fig. 8 is a front elevation of Fig. 7. Referring to Fig. 1, switch 49 is provided with two electrodes, 80 and 81, mounted in tubular chambers 82 and 83 and which have connected to them the lead in wires, 87 and 88, respectively, which are sealed through the walls of their respective chambers. The capillary or flow restriction tube, 85, connects the chambers 82 and 83 near their bottoms and has sealed into it the terminal electrode 86.

In one form of my switch sufficient mercury is sealed in the tube to electrically connect all three electrodes 80, 81 and 86 when the switch is in the upright position as shown in Fig. 3, but the quantity is provided such that when the switch is tipped to one side or the other the mercury flows from one of the chamber electrodes to disrupt the electrical connection on that side, the mercury assuming a position similar to that shown in Fig. 1 or 2. The restriction on the flow of the mercury by the tube 85 provides that such disruption does not occur until a definite time after the tipping of the switch, such time being predetermined by the design of the switch involving such elements as the size of the tube 85, the amount of mercury in the switch, the positions of the electrodes and so on.

In another form of my switch as shown in Fig. 4 connection is disrupted throughout the switch when the mercury in the two chambers is about the same in quantity. Such a condition would exist when the switch is left to stand at or near the vertical position sufficiently long for the mercury to come to or near gravimetric equilibrium. Such also is the condition of the switch at one stage in the flow of the mercury after each tilt from one side to the other. In the form shown in Fig. 3 a similar condition would exist but in that case electrical connections would be established throughout the switch at such positions.

In my switch the tube 116 connecting the electrode terminal chambers 82 and 83 near their tops serves to allow an equalization to take place between the gases or vapors in said chambers.

The first of these forms above mentioned can be used without using the electrode 86 or the switch may be made without this electrode. In such case the mercury is used to make and break connection between the electrodes 80 and 81, the tube 85 serving to regulate the interval at which the make or break is made after the movement of the switch.

Or my switch with the electrode 86 can be used for making and breaking a complication of circuits such for instance as is shown in my copending application, Serial No. 359,882, filed Feb. 19, 1920, patented March 29, 1927, No. 1,622,519, of which this application is, in part, a continuation.

In Fig. 6 of the drawings is shown my switch in the electrical control system of a refrigeration apparatus. In this figure is shown a still or distillation chamber, 13, in which is situated a suitable electrical heating coil (not shown) connected through wires 1 and 2 to electric supply mains 11 and 12, respectively. Between lead 2 and main 12 are connected suitable control mechanisms hereinafter further described. A condensing chamber 16 is connected to the still 13 by the

pipe 17, manifold 18, check valve 19 and pipe 20.

The check valve allows refrigerant vapor of the system to pass through it from still 13 to condenser 16 but prevents flow through it in the opposite direction. From the condensing chamber 16 pipe 24 is provided for the refrigerant condensed therein to pass therethrough to the refrigeration chamber 25. From the refrigeration chamber 25 connection is made through pipe 27, check valve 28, manifold 18, and pipe 17 to still 13. The check valve 28 allows the refrigerant to flow through it from the chamber 25 to still 13, but prevents flow through it in the opposite direction.

In connection with the still 13 and condensing chamber 16 is a cooling system of water supply and distribution pipes, a cooling coil for the condensing chamber and one for the still chamber (both shown in dotted lines), and an electrically controlled two-way valve 29 which latter serves to direct the flow of the water alternately through the cooling coils of said still 13 and chamber 16. The pipe 30 connects the cooling system to the water supply mains through said two way valve 29. The pipe 31 connects the main 30 through one position of valve 29 to the cooling coil (not shown) of still 13 which discharges through pipe 39 to discharge pipe 35. The main 30 is connected through valve 29 at its other position through pipe 32 to the cooling coil (not shown) of still 16, thence through pipe 34 to discharge pipe 35.

The valve 29 is operated to direct the flow of water either through pipe 31 or pipe 32 by means of a double armature 42, one end of which works in solenoid 40 and the other end in solenoid 41. By means of an automatic system of electric switches hereinafter described the solenoids are alternately energized to cause the plunger 42 to move to actuate valve 29 to alternately direct water through the cooling coils of the still and the condenser.

The periodic flow of current through heating coil of the still and the flow of water through valve 29 alternately to the cooling coil condenser 16 and to cooling coil of the still 13 are controlled by means of an electrical system including switches 48, 49, 50 and 51 and a switching arrangement in refrigerating chamber 25. The switches 48, 49, 50 and 51 are mounted on a rocking beam 67 (see Figs. 7 and 8) which is controlled and actuated by the armatures 54 and 55 which work in solenoids 52 and 53 respectively as fully set forth in my prior application filed February 19, 1920, Serial No. 359,882. Switch 48 makes and breaks a connection in the circuit of solenoid 40, one side of which is connected through wire 5 to one side of said switch 48 and the other side through wire 4 to the main 11. The other side of switch 48

is connected both to one side 49a of time switch 49 and to one side of solenoid 52, the other side of said solenoid 52 being connected to the wire 56 and through it to contact 57 in said refrigerator chamber 25. Mounted on float 62 within said chamber 25 is a contact making disc 58 which, when float 62 is at its upper limit of movement, makes contact with said contact 57 and a corresponding contact 59 which latter with wires 60 and 61 make connections with main 11. The midpoint 49c of switch 49 is connected to main 12 through wire 8. The side 49b of switch 49 is connected through wire 10 both to switch 50 and solenoid 53. The other side of switch 50 is connected through wire 9 and solenoid 41, through wire 4 to the main 11. The other side of solenoid 53 is connected through wire 63, contact 64, contacting disc 58, contact 65, wire 66, wire 61 to main 11. The switch 51 is connected on one side to main 12 and on the other to the heating coil 15 and thence to main 11.

The operation of the refrigerating system 25 of my invention as described above is as follows, starting with the switching apparatus in the position shown in Fig. 6, with the electric mains 11 and 12 connected to a source of current and with no refrigerant in the 30 refrigerating chamber 25. The refrigerant will be in the still 13 physically or chemically combined with the absorbent material, and the heating coil thereof will be energized. When sufficient heat has been generated in 35 the still the vaporized fluid will be forced by the resulting pressure through pipes 17 and 20 into the condenser chamber 16. Valve 29 being open on the condenser side, the water flowing through the cooling coil thereof 40 will cool the fluid in chamber 16, causing it to condense. When a sufficient quantity of liquid has collected in chamber 16 a valve 45 therein (not shown) will be float operated to open thereby allowing the liquid to flow through pipe 24 into the refrigerator chamber 25, where it collects. This collection and discharge occurs repeatedly and as the level of the liquid in chamber 25 rises it carries float 62 upward and lifts contact member 50 55 up to contacts 57 and 59 whereby an electrical connection therebetween is established.

Current will then flow from main 11 through conductor 61, conductor 60, contact 59, contactor 58, contact 57, conductor 56, solenoid 52, conductor 7, switch 49, conductor 8 to main 12, thereby energizing the solenoid 52, the armature 54 of which being actuated will pull the switch bar (not shown) down. Switches 50 and 51 will then be open, 51 cutting off the heating current to the heating coil 15. Switch 48 will be closed and the 49a side of time-switch 49 will remain closed for five seconds, the time required for the mercury to flow through the constriction in time-switch 49. A circuit then for five seconds

will be established for main 11, wire 4, solenoid 40, wire 5, switch 48, wire 7, the 49a side of switch 49, terminal 49c, wire 8, to main 12, whereupon solenoid 40 will be energized and valve 29 actuated to close the port to 70 cooling coils 33 and to open the port to pipes 31 and 37 and to cooling coils 36 and 38 whereby still 13 is cooled. The current passing through solenoid 40 for five seconds insures the moving of the valve 29 to its proper position. The cooling of the still 13 results in a considerable decrease in pressure therein and in refrigerating chamber 25. With the decrease in pressure there is a rapid vaporization of the liquid in refrigerating chamber 25 and a consequent decrease in temperature. The vaporization and decrease in temperature in chamber 25 continue until contact is made by contactor 58 between contacts 64 and 65, switch 51 is closed 75 and pressure raised in still 13.

As the liquid in chamber 25 vaporizes its level therein falls and with it the float 62 until the contactor 58 strikes contacts 64 and 65 whereby the circuit is closed from conductor 11, through conductors 61 and 66, contact 65, contactor 58, contact 64, conductor 63, solenoid 53, switch 49 (side 49b), conductor 8, to main 12. The solenoid 53 now being energized and solenoid 52 de-energized, 90 switch 48 will be opened, switches 50 and 51 will be closed, and switch 49b will remain closed for a period of five seconds during which solenoid 41 will be energized for the 95 actuation of valve 29 to close the port to pipes 31 and 37 and to the cooling coils of still 13 and to open the port through pipe 32 to the cooling coil of the condenser 16 whereby 100 chamber 16 is cooled. Heating current now flows through heating coil 15 in still 13 and 105 cooling water flows through the condenser coils, the water through still coils being turned off.

Again the vaporized refrigerant will pass from the still 13 to the condenser 16 where it 110 condenses and accumulates until there is sufficient therein to raise the float valve therein. The liquid again flows into the refrigerator for evaporation when the contactor 58 closes, the circuit through solenoid 52 and a decrease in pressure in still 13 is effected by the 115 cooling thereof. The distillation, condensation and refrigeration cycle is thus carried on repeatedly while mains 11 and 12 are energized.

Here is shown an application of my switch for keeping an electrical circuit closed for a definite period after the passing of current therethrough is established to insure the proper and certain functioning of the device 125 energized therethrough. From the use in the above described system, and in the system described in my copending application Serial Number 673,105, filed November 6, 1923, as well as from the above description of my 130

switch it can be seen that my invention is capable of application in a number of ways and with various kinds of machinery, apparatus, etc.

5. I claim:

1. In an electrical control system, the combination of two switches for opening and closing electrical circuits therethrough, means for moving said switches to simultaneously close a circuit through one switch and open another circuit through another switch, and liquid level controlled means for closing and opening alternately the circuit of said first named means.
10. 2. In an electrical control system, the combination of two switches for opening and closing electrical circuits therethrough, means for moving said switches to simultaneously close a circuit through one switch and open another circuit through another switch, and liquid level controlled means for closing and opening alternately the circuit of said first named means, and means for opening the circuit to a closed switch after 25 a time interval.
15. 3. In a refrigeration apparatus having a generator connected to a condensing chamber, a refrigeration chamber having upper and lower sets of electric contacts mounted thereon and being connected to said generator and to said condenser chamber, heating means for said generator, and means for circulating cooling water to said generator and to said condenser chamber both fed from the 30 same source through an electrically operated two-way valve, in combination, a three electrode mercury switch having one electrode alternatively common to the other two, and mercury switches having electrodes in each 35 end thereof, and means in the first named switch to retard the flow of mercury therein to hold the mercury in one electrode uniting position for a definite period of time after the switch has been moved into the other electrode uniting position, and a float in said 40 refrigeration chamber carrying a contactor which establishes electrical circuit through the upper set of electric contacts and said switches at the upper limit of movement of 45 said float to deenergize said heater and to actuate said electrically operated two-way valve to turn water from said generator cooling means and to turn water to said condenser chamber cooling means and at the 50 lower limit of such movement through the lower set of contacts and said switches to energize said heater and to actuate said electrically operated two-way valve to turn cooling water from said generator cooling means 55 and to turn water to said condenser chamber cooling means.
60. 4. In a refrigerating apparatus, in combination, a generator connected through a one-way conduit into a condensing chamber, a refrigerating chamber, connection between the condensing chamber and the refrigerating chamber, a one-way conduit from the refrigerating chamber into the generator, a cooling coil for the generator, a cooling coil for the condensing chamber, a two-way 70 valve connected from a source of supply for alternative distribution to said coils, an electro-magnet magnetically connected to said valve to open it to the generator coil and close it to the condensing chamber coil, 75 a second electrode-magnet magnetically connected to said valve to open it to said condensing chamber coil and close it to said generator coil, mercury-switch electrodes in the respective circuits of said magnets and 80 positively mounted with respect to each other and the contacting mercury to close the circuit upon the opening of the circuit of the other of said electro-magnets and a liquid level control contactor and upper and 85 lower sets of contacts in said refrigerating chamber for closing the circuits of said electro-magnets.
90. 5. In a refrigerating apparatus, in combination, a generator connected through a one-way conduit into a condensing chamber, a refrigerating chamber, connection between the condensing chamber and the refrigerating chamber, a one-way conduit from the refrigerating chamber into the generator, a cooling coil for the generator, a cooling coil for the condensing chamber, a two-way valve connected from a source of supply for alternative distribution to said coils, an electro-magnet magnetically connected to 95 said valve to open it to the generator coil and close it to the condensing chamber coil, a second electro-magnet magnetically connected to said valve to open it to said condensing chamber coil and close it to said generator coil, mercury-switch electrodes in the respective circuits of said magnets and positively mounted with respect to each other and the contacting mercury to close the circuit upon the opening of the circuit of the other of said electro-magnets, and a time switch connected in series with each of said magnet circuits with means therein for opening the circuits thereof at a predetermined time after the establishing of a circuit therethrough and a liquid level control contactor and upper and lower sets of contacts in said refrigerating chamber for closing the circuits of said electromagnets.
100. In testimony whereof I hereto affix my 110 signature.

FREDERICK G. KEYES.
